United States Patent Office

Des. 183,960
Patented Nov. 25, 1958

183,960

CART FOR BASEBALLS AND BATS

Robert C. Carroll, Bakersfield, Calif., assignor of one-third to G. M. Juzek, Porterville, Calif., and one-third to Lloyd C. Snider, Bakersfield, Calif.

Application January 17, 1958, Serial No. 49,291

Term of patent 14 years

(Cl. D14—3)

I claim:

The ornamental design for a cart for baseballs and bats, as shown.
